(57) **CLAIM**

The ornamental design for an adjustable weight bench, as shown.

DESCRIPTION

FIG. 1 is a perspective view of an adjustable weight bench showing the new design having components thereof in a first position.

FIG. 2 is a right elevation view of the adjustable weight bench of FIG. 1.

FIG. 3 is a left elevation view of the adjustable weight bench of FIG. 1.

FIG. 4 is a front elevation view of the adjustable weight bench of FIG. 1.

FIG. 5 is a rear elevation view of the adjustable weight bench of FIG. 1.

FIG. 6 is a top plan view of the adjustable weight bench of FIG. 1.

FIG. 7 is a bottom plan view of the adjustable weight bench of FIG. 1.

FIG. 8 is a perspective view of the adjustable weight bench of FIG. 1 having the components thereof in a second position.

FIG. 9 is a right elevation view of the adjustable weight bench of FIG. 8.

FIG. 10 is a left elevation view of the adjustable weight bench of FIG. 8.

FIG. 11 is a front elevation view of the adjustable weight bench of FIG. 8.

FIG. 12 is a rear elevation view of the adjustable weight bench of FIG. 8.

FIG. 13 is a top plan view of the adjustable weight bench of FIG. 8; and,

FIG. 14 is a bottom plan view of the adjustable weight bench of FIG. 8.

The broken lines depict portions of the adjustable weight bench that form no part of the claimed design.

1 Claim, 14 Drawing Sheets
